UNITED STATES PATENT OFFICE.

WILLIAM HUMBAUGH, OF DAYTON, OHIO.

HOSE-SUPPORTING DEVICE.

1,036,120.

Specification of Letters Patent. Patented Aug. 20, 1912.

Application filed February 8, 1912. Serial No. 676,376.

To all whom it may concern:

Be it known that I, WILLIAM HUMBAUGH, a citizen of the United States, residing at Dayton, in the county of Montgomery and 5 State of Ohio, have invented new and useful Improvements in Hose-Supporting Devices, of which the following is a specification.

This invention relates, broadly, to the class of devices adapted to handle fire hose 10 and more specifically to that class of hose handling devices wherein is embodied means for facilitating the attachment and detachment of the hose to and from the device.

An object of my invention is to provide a 15 hose handling apparatus which is constructed only of a few parts thereby reducing to a great extent the loss of energy due to friction.

A further object of my invention is to 20 provide a device of the above character which is simple in construction and which may be manufactured and placed upon the market at a comparatively low cost.

With the foregoing and many other objects in view my invention relates to such 25 details of construction and in the arrangement and combination of parts as will be hereinafter fully described and specifically pointed out in the appended claims.

30 In describing my invention in detail reference will be had to the accompanying drawings wherein like characters denote like or corresponding parts throughout the several views, and in which:—

35 Figure 1 is a plan view of my invention. Fig. 2 is a fragmentary view of my invention. Fig. 3 is a vertical sectional view. Fig. 4 is a side elevation of a detail.

In the accompanying drawings which 40 fully illustrate the preferred form of my invention 1 designates the supporting members of my device which members are connected together at their upper ends so as to receive a tubular member 2 which member 45 has the ratchet teeth 3 formed at one side, which teeth are engaged by a pivoted pawl 4, it being held in engagement therewith by means of the coiled spring 5. One of the supporting members 1 is provided at its 50 lower end with a hook 6, while the others are provided with the rollers 7, the hook serving a purpose that will presently appear. Carried by the lower end of the tubular member 2 and supported by a bracket 8 is 55 a wheel 9 which has proven advantageous

in the adjustment of the member 2. Seated over the upper portion of the member 2 is a collar 10, which collar supports near its outer end a plurality of ball bearings 11 which engage a depending flange 12 which is formed upon the circular top 13. It is now obvious that the top 13 may be readily revolved in relation to the supporting standards. The hollow member 2 also receives a shank 14 which has a head portion 15 formed thereon, the shank being also journaled through a member 16 which is carried by the top 13. Ball bearings 17 are positioned between the member 16 and the head 15 for an obvious purpose. The top 13 is 70 provided with the screw-threaded plug 18 whereby admittance may be had to the member 16 and the ball bearings 17. By providing this plug it is readily seen that the working of the machine is assured. For the purpose of holding the shank 14 securely in engagement with the member 2 the means 19 are provided, they being journaled through the same member.

For a purpose that will presently appear 80 a plurality of arms 20 are secured to the collar 10 and support at their upper ends the handles 21. Also carried by the collar 10 is another arm 22 which has a sleeve 23 pivotally connected thereto, the said sleeve having a rod 24 slidably mounted thereon and adapted to support the bifurcated clasp 25 as shown.

In the operation of my device the end of the hose is moved into engagement with the 90 clasp 25 and the hose may be readily wound around the same as shown in Fig. 1. It is readily obvious that the handle portions 21 prevent the hose from partly falling from the top. It will be also readily seen that the 95 clasp may be adjusted at different positions along the top and if desired lifted from engagement therewith so that the quantity of hose held on the top may be quickly removed therefrom.

I desire to lay the greatest of stress upon the simplicity of my device and it is thought that the advantages and novel features of the same will be appreciated from the foregoing disclosure.

I desire it to be understood that I may make slight changes in the construction of my invention without departing from the spirit thereof, provided such changes fall within scope of the subjoined claims.

Having thus fully described my invention what I claim as new and desire to secure by Letters Patent is:—

1. In a device of the character described, a supporting structure having a top revolvably mounted thereon, a plurality of arms carried by said supporting structure, said arms being adapted to support handles, another arm carried by said supporting structure, a sleeve pivotally connected to said last named arm, and means carried by said sleeve adapted to engage a hose, for the purpose described.
2. In a device of the character described, a supporting structure, means for adjusting said supporting structure vertically, a circular top revolvably mounted upon said supporting structure, a plurality of handles supported by said supporting structure, an arm connected to said supporting structure, a sleeve pivotally connected to said arm, a rod slidably mounted upon said sleeve, and a clasp carried by said rod, for the purpose described.
3. In a device of the character described, supporting standards having a tubular member slidable vertically therethrough, ratchet teeth formed upon one side of said tubular member, a pawl carried by said supporting standards adapted to engage said ratchet teeth, a circular top revolvably supported by said tubular member, and handles arranged above said circular top and supported by said tubular member, for the purpose described.
4. In a device of the character described, a tubular member supported by a plurality

of standards, ratchet teeth formed upon one side of said tubular member, a pawl carried by said supporting standards adapted to engage said teeth whereby said tubular member may be adjusted vertically, a collar mounted upon the upper end of said tubular member, ball bearings disposed upon said collar, a circular top provided with a depending flange, said flange adapted to engage said rollers, and a plurality of handles mounted above said top and supported by said collar, for the purpose described.

5. In a device of the character described, a tubular member vertically slidable therethrough, ratchet teeth formed upon said member, a pawl carried by said supporting standards adapted to engage said teeth whereby said member may be held in an adjusted position, a collar supported by the upper end of said tubular member, a circular top having a flange depending therefrom, ball bearings disposed upon said collar adapted to be engaged by said flange, a shank disposed in said tubular member, a head formed upon said shank, a member carried by the underside of said top, ball bearings disposed between said member and said head, a screw-threaded plug positioned within said circular top, an arm carried by said collar, a sleeve pivotally connected to said arm, a rod slidably within said sleeve, and a clasp positioned upon said rod, for the purpose described.

WILLIAM HUMBAUGH.
